GLASS WORKING TOOL

Robert A. Yuchtmann, Weston, W. Va.

Application March 29, 1937, Serial No. 133,677

1 Claim. (Cl. 49—22)

This invention relates to glass working tools employed for finishing the base of stem glassware after joining of the unfinished base on the stem and has for the primary object the provision 5 of a device of this character which will form a selected design on the base of the glassware simultaneously with the finishing operation above mentioned thereby rendering the glassware more artistic or attractive and consequently more saleable.

With these and other objects in view, this invention consists in certain novel features of construction, combination and arrangement of parts to be hereinafter more fully described and 15 claimed.

For a complete understanding of my invention, reference is to be had to the following description and accompanying drawings, in which

Figure 1 is a top plan view illustrating my invention in use for the purpose of designing the base of stem glassware after the application of the base to the stem.

Figure 2 is a side elevation illustrating my invention attached to a finishing tool for stem glassware.

Figure 3 is a sectional view taken on the line 3—3 of Figure 2.

Figure 4 is a sectional view taken on the line 4—4 of Figure 3.

Figure 5 is a detail plan view illustrating a modified form of my invention.

Figure 6 is a fragmentary edge elevation illustrating the same.

Referring in detail to the drawings, the numeral 1 indicates a conventional type of finishing tool especially adapted for finishing a base of stem glassware after the joining of the base to the stem, as shown in Figure 1, and prior to detaching the blow tube 2 from the glassware 3. Glassware 3, as shown in Figure 1, is formed in the usual way by employing the blow tube 2, the body and stem of the glassware being blown and after the blowing thereof and while still hot the base 4 is joined to the end of the stem. The

base 4 is a piece of hot glass. After joining of the base to the stem while still hot, the base is rotated while in contact with polishing or finishing blocks 5 and 6 carried by the tool. The rotation of the base of the glassware is accomplished by the operator rolling the blow tube back and forth over a rest holding the tool 1 in the other hand so that the surfaces of the base will be polished. Heretofore, the edges of the base are smooth and annular. In order to render this

base more artistic or attractive my invention is adapted to the tool 1 so that a selected design may be formed in the edges of the base during the finishing of said base by rotating it relative

to the finishing elements 5 and 6 of the tool. The attachment consists of a bracket 7 suitably secured to the tool 1 and to which are pivoted connected arms 8 each arcuately curved. A head 9 is secured on the arms and has a slot 10 to slidably receive an axle 12 on which is journaled a roller 13 provided with anti-friction bearings 14. A rod 9' is slidably mounted in the head 9 and is connected with the axle, and mounted on said rod 9' and interposed between the head 9 and the axle is a coil spring 15 acting to urge the roller in engagement with the work. Formed on the periphery of the roller 13 is a pattern or design of some selected kind. The arms 8 are capable of occupying different positions by being pivoted on the bracket 7 and when in one position bring the periphery of the roller in contact with the base of the stem glassware, as shown in Figures 1 and 2, and when the arms are in another position the roller will be positioned laterally of the base permitting the glassware to be easily removed from the tool. The spring 15 will act to force the roller or the periphery of the latter against the edges of the base of the stem glassware with sufficient force so that as the glassware is rotated the base will have impressed in the edges thereof the design on the periphery of the roller, consequently permitting the design to be formed on the base at the same time the said base is finished or polished in the manner heretofore described.

Referring to my modified form of the invention, as shown in Figures 5 and 6, a bracket 16 is secured to the tool 1 and has secured thereto supporting rods 17 on which is slidably mounted a head 18. Journaled on the head is the roller 13. Springs 19 are mounted on the rods 17 and act to urge the head 18 towards the bracket 16 and the periphery of the roller in engagement with the edges of the base of the stem glassware. Threaded on the rods 17 are wing nuts 20 bearing against a plate 21 slidable on the rods 17 and engaging the springs 19 whereby the tension of said springs can be adjusted.

What is claimed is:

In combination with a glassware base finishing tool, a bracket secured on the tool, arms pivoted on said bracket, a head secured on said arms and having a slot, an axle slidable in said slot, a roller journaled on said axle and having a design on its periphery to contact and form on a base of stem glassware said design during the finishing of the base by said tool, a rod slidable in the head and connected to the axle, a spring mounted on said rod and acting on the axle to urge the roller in contact with the base.

ROBERT A. YUCHTMANN.
